Primary Examiner—Raphael Barkai(74) **Attorney, Agent, or Firm**—Kolisch Hartwell Dickinson McCormack & Heuser, PC**(57) CLAIM**

The ornamental design for a children's ride-on vehicle, as shown and described.

DESCRIPTION

FIG. 1 is a front perspective view of a children's ride-on vehicle showing the claimed design.

FIG. 2 is a left side elevation view of the vehicle of FIG. 1.

FIG. 3 is a rear perspective view of the vehicle of FIG. 1.

FIG. 4 is a right side elevation view of the vehicle of FIG. 1.
FIG. 5 is a front elevation view of the vehicle of FIG. 1.
FIG. 6 is a rear elevation view of the vehicle of FIG. 1.
FIG. 7 is a top plan view of the vehicle of FIG. 1.
FIG. 8 is a rear perspective view of the vehicle of FIG. 1 with environment shown in dashed lines; and,

FIG. 9 is a right side elevation view of the vehicle of FIG. 1 with environment shown in dashed lines.
The broken lines shown in FIGS. 5, 8 and 9 are for illustrative purposes only and form no part of the claimed design.
